UNITED STATES PATENT OFFICE.

BANCROFT G. BRAINE, OF NEW YORK, N. Y., ASSIGNOR TO THE RAIL JOINT COMPANY,
A CORPORATION OF NEW YORK.

INSULATED RAIL-JOINT.

1,204,124.

Specification of Letters Patent. Patented Nov. 7, 1916.

Application filed July 10, 1916. Serial No. 108,432.

To all whom it may concern:

Be it known that I, BANCROFT G. BRAINE, a citizen of the United States, residing at New York, in the county of New York and 5 State of New York, have invented certain new and useful Improvements in Insulated Rail-Joints, of which the following is a specification.

This invention relates to insulated rail joints and has particular reference to a 10 novel improvement in the means for insulating the bolts from the joint bars in joints of this type.

Heretofore, it has been the general practice to employ fiber ferrules or sleeves around the bolts to prevent the latter from 15 contacting with the splice bar, and in service these ferrules become ruptured or worn, and frequently need replacing. The disintegration of these ferrules is, for the greater part, due to the end-wise movement of the 20 rails, the pressure of which is usually taken up by the sides of the bolt holes in the splice bar, thus subjecting the ferrule to a stress 25 which causes the same to become thin and often completely break at this point, making a short circuit or current leakage. In order to place a new ferrule around the shank of the bolt, it is necessary to dismember the 30 joint, which involves considerable trouble and expense.

Accordingly, the present invention proposes to provide an improved bolt insulation of such form and arrangement as to 35 effectually prevent current leakage or short circuiting through the bolts. At the same time, the invention permits the bolts to have an ample clearance through the splice bar, so that the pressure, due to the end-wise 40 movement of the rails, will not come against the sides of the holes in the splice bar, but is transferred to another portion thereof which is capable of being easily insulated from an accessible position, thus facilitating 45 the renewal of the insulation, and at the same time providing a relatively large and uniform bearing surface for the insulating fiber as compared with the side of the bolt holes in the splice bar. Therefore, it will 50 be apparent that the novel and distinctive feature of the present invention is the provision of means whereby the end-wise pressure of the rails is removed from the sides of the bolt holes of the splice bar, and trans-

ferred to other portions of the latter especially adapted to withstand the pressure, and serving to hold the bolts centered in the bolt holes.

As a further object, the invention contemplates means of the character set forth, 55 which are susceptible of embodiment in, or application to, joint bars of standard section, without in any way affecting the structural features thereof, and which are located in a relatively exposed position, and consequently are readily accessible for the 60 purpose of facilitating renewals and the like.

With the above and other objects in view 65 which will more readily appear as the nature of the invention is better understood, the same consists in the novel construction, combination, and arrangement of parts hereinafter more fully described, illustrated and claimed.

Preferred and practical embodiments of 70 the invention are shown in the accompanying drawings, in which—

Figure 1 is a perspective view of an insulated rail joint, showing the present invention applied thereto. Fig. 2 is an enlarged detail longitudinal sectional view taken through the bolt insulating unit, shown in Fig. 1. Fig. 3 is a view similar to Fig. 1, showing a slightly modified form of 75 the invention. Fig. 4 is a view similar to Fig. 2, showing the modification of Fig. 3. Fig. 5 is a vertical sectional view of the construction shown in Fig. 3, taken at one of the bolts. Fig. 6 is a perspective view of 80 a joint bar showing a still further modification of the invention. Fig. 7 is an enlarged detail longitudinal sectional view of one 85 complete insulating unit used in connection with the joint bar, shown in Fig. 6. Fig. 90 8 is a vertical sectional view of the construction shown in Fig. 7, the line of section being taken at one of the bolts.

Similar reference characters designate corresponding parts throughout the several figures of the drawings.

As previously indicated, the present invention is susceptible of application to any joint bar of the insulated type, and as illustrating the use of the invention in connection with joint bars already in use, reference may be had to Fig. 1 of the drawings, 105 which shows continuous joint bars 1—1 held

to the rails R by the usual bolts 2 projecting through the bolt holes 3 in the web 4 of the joint bar.

The nut ends of the bolts 2 are insulated from the web 4 of the joint bar by means of a novel insulating unit, designated in its entirety by the reference letter A, and essentially comprising in its organization a pressure transferring element 5, in the form of an elongated washer plate having bolt receiving openings 6, which snugly fit the shanks of the bolts 2, and thus hold the same in the bolt holes 3. Between the pressure transferring element 5 and the outer face of the web 4 of the joint bar, there is interposed an insulating shoe 7 having the angularly disposed end portions 8 for completely protecting the ends of the pressure transferring element or washer plate, as shown in Fig. 2. This arrangement, therefore, completely insulates the nut ends of the bolts 2 from the joint bar 1, and maintains the bolts in their original position in the bolt holes 3, so that when the nuts 9 are applied to the bolts, the pressure transferring element is rigidly clamped against the outer face of the web of the joint bar and firmly held in an insulated position. Accordingly, since the bolts 2 are engaged with the webs of the rails, and are rigidly coupled by means of the pressure-transferring element 5, it will be apparent that any movement of the rails will be transmitted by the bolts 2 directly to the said pressure transferring element or washer plate, and in order to transmit this pressure to the joint bar, so that the bolts will remain centered in the bolt holes, the web 4 of the joint bar is provided with the abutment shoulders 10. These abutment shoulders may be in the form of angle plates riveted or otherwise permanently secured to the splice bar, as shown in Fig. 2, and are located at opposite sides of the paired bolt holes 3, thus constituting a rigid abutment for receiving the end-wise pressure of the rails transmitted through the bolts to the washer plate 5, and providing a relatively large and uniform flat bearing surface for the ends 8 of the insulating shoe, which produces much less wear on the latter than the sides of the bolt holes do on the ferrules now in general use. This form of the invention illustrates the application thereof to joint bars now in use, and locates the entire insulating unit in an exposed and readily accessible position at the outer face of the web of the joint bar, whereby the condition of the insulating shoe 7 may be readily observed and inspected, and renewed when necessary by simply removing the nuts 9 from the end of the bolts 2 and withdrawing the washer plate from the shanks of the bolts.

The novel features of the invention may also be carried into effect in the modified way shown in Fig. 3 of the drawings,

wherein the abutment shoulders are formed by recessing the web 4^a of the splice bar 1 to provide an elongated socket 11 adjacent the paired bolt holes 3, whose end walls 12 constitute flat abutment shoulders against which the ends 8 of the insulating shoe 7 are clamped by means of the washer plate 5. Thus, this form of the invention provides for centering the bolts 2 in the bolt holes 3, and when the nuts 9 are screwed onto the ends of the bolts, the plate 5, which rigidly connects and couples the paired bolts, is held firmly in the socket 11 to clamp the insulating shoe in position, and thus effectually insulate the bolts from the joint bar. This construction has the advantage of locating the washer plate or pressure transferring element substantially within the limits of the joint bar. That is to say, the provision of the socket 11 permits the plate 5 to fit into the joint bar in such a way that only enough thereof projects beyond the outer face of the web of the splice bar to permit the insulation of the unit to be readily inspected. In connection with this embodiment of the invention, it will be noted that the insulating shoe 5, in addition to the angular ends 8, includes the side portions 8^a of insulation which are interposed between the upper and lower sides of the washer plate and corresponding sides of the socket 11 to thus completely insulate the plate from the joint bar.

Another form of the invention is shown in Fig. 6 of the drawings, and structurally the same is of substantially the same general nature as the form of the invention shown in Figs. 3, 4, and 5, except, however, that the web 4^b of the joint bar 1 is formed with the socket 13, which is slightly shallower than the socket or recess 11, in the figures referred to. At each end of the recess the bar is provided with the offset integral abutment shoulders 14 by upsetting the metal from the ends of the recess. These shoulders project beyond the outer face of the web of the joint bar, as shown, and provide the same relatively large and uniform flat bearing surface for the insulation, as is provided in the other form of the invention, even though the depression of the joint bar which receives the pressure transferring plate 5 is relatively shallow.

As shown in Fig. 7, the pocket 13 receives the insulating shoe 7, having the angular end portions 8 and flanged sides 8^a for insulating the ends and sides of the washer plate or pressure transferring element 5 from the bar.

Therefore, in all forms of the invention, the features of a relatively large bearing surface for the insulator and accessibility of the latter are maintained through the provision of an insulating unit exposed at the outer face of the joint bar, thus greatly adding to the life and service of the insulating

shoe. As the bearing faces of the abutment shoulders are flat and the ends of the washer plate are also flat, the pressure on the insulation is evenly distributed, and no single portion thereof cuts out more rapidly than another, as in the case of a ferrule surrounding a bolt in a circular bolt hole. 5

Without further description, it is thought that the many features and advantages of the invention will be apparent, and it will, of course, be understood that changes in the form, proportion and minor details of construction may be resorted to without departing from the spirit of the invention or 10 the scope of the appended claims.

I claim:

1. An insulated rail joint including in combination with the rails and joint bolts, a splice bar having bolt holes and abutments adjacent thereto, and an insulated pressure-transferring element engaging the bolts and said abutments. 20

2. An insulated rail joint including in combination with the rails and joint bolts, a splice bar having bolt holes, and rigid abutments adjacent thereto, and an insulated pressure-transferring element snugly fitting said bolts and engaged by said rigid abutment means. 25

3. An insulated rail joint including in combination with the rails and joint bolts, a splice bar having bolt holes, and abutment means adjacent thereto, and insulated means carried by said bolts for engaging with said 30 abutment means to center the bolts in the bolt holes in the splice bar.

4. An insulated rail joint including in combination with the rails and joint bolts, a splice bar having holes for loosely receiving the bolts, and rigid abutment means adjacent said holes, and insulated means carried by said bolts for transferring end-wise pressure of the rails to said abutment means. 40

5. An insulated rail joint including in combination with the rails and joint bolts, a splice bar having bolt holes and also having abutment elements disposed on opposite sides of said bolt holes, and insulated means carried by said bolts for transferring end-wise pressure of the rails to said abutment 45 means. 50

6. An insulated rail joint including in combination with the rails and joint bolts, a splice bar having spaced paired bolt holes, and abutment elements arranged in opposed relation adjacent said paired bolt holes, and an insulated pressure-transferring element carried by the bolts projecting through said paired bolt holes and interlocked with said abutment elements. 55

7. An insulated rail joint including in combination with the rails and joint bolts, a splice bar having bolt holes and abutment elements arranged in opposed relation adjacent certain of said holes, and an insulated pressure-transferring element carried by the ends of said bolts passing through said holes and arranged in an exposed position at the outer face of the web of the bar and fitting between said abutment elements. 60

8. An insulated rail joint including in combination with the rails and joint bolts, a splice bar having bolt holes, and rigid abutment shoulders adjacent said holes, an insulated washer plate snugly fitting said 70 bolts and limited in its movement by engagement with said rigid abutment means.

9. An insulated rail joint including in combination with the rails and joint bolts, a splice bar having bolt holes for receiving the bolts, and also having abutment shoulders arranged in opposed relation adjacent said holes, a washer element carried by said bolts and in metallic engagement therewith, and an insulation shoe interposed between 80 one face of the washer element and the splice bar and also between the ends thereof and the abutment shoulders, said washer element and shoe being interlocked between 85 said shoulders. 90

10. An insulated rail joint including in combination with the rails and joint bolts, a splice bar having bolt holes, and also having a depression adjacent said holes and abutment shoulders located at the ends of 95 said depression, and an insulated pressure-transferring element rigidly carried by said bolts and having the ends thereof in abutting engagement with said shoulders.

In testimony whereof I hereunto affix my 100 signature.

BANCROFT G. BRAINE
